Glossary

UNITED STATES PATENT OFFICE.

ELDEN L. SMITH, OF MARSHFIELD, OREGON.

HOISTING SLING.

Application filed April 25, 1925. Serial No. 25,845.

To all whom it may concern:

Be it known that I, ELDEN L. SMITH, a citizen of the United States, residing at Marshfield, in the county of Coos and State 5 of Oregon, have invented certain new and useful Improvements in Hoisting Slings, of which the following is a specification.

The present invention relates to new and useful improvements in hoisting slings, more 10 particularly adapted for use in connection with the hoisting of rocks, large stones, and the like.

It is the object of the present invention to provide a comparatively simple and readily 15 attachable sling member for stones and the like, which is adapted for engagement with a hoisting means, whereby the stone may be hoisted and conveyed to a desired position, and then released when rested on the sup- 20 port.

Another important object of the invention is to provide a device of this nature, which is easily engageable with a rock or the like, and which is easily disengageable therefrom.

25 A still further object of the invention is to provide a rattling sling of this nature, which may be manufactured at a comparatively low cost, and yet be strong, durable, reliable, not likely to become easily out of order, and otherwise well adapted for the purpose for which it is designed.

With the above and other objects and advantages in view, the invention resides more particularly in the novel combination, for- 35 mation and arrangement of parts more particularly hereinafter described and claimed.

In the drawing:

Figure 1 is an elevation of the hoisting sling embodying the features of my invention.

Figure 2 is another elevation thereof, taken at right angles to that shown in Figure 1.

Referring to the drawing in detail, it will 45 be seen that 1 designates a plate having a centrally located opening therein, preferably provided with a rolled edge. The ends of this plate terminate in eyes 3, to which are pivotally attached links 4. Jaws 5 are pivotally engaged with the links 4 and are preferably curved throughout their length. On the inner sides of the extremities of the jaws 5 there are disposed pointed spurs 6, which are adapted to engage the rock which is in-

dicated in the drawing. Shields 7 are constructed with offset ends fixed to the outsides of the jaws 5, so that the major portions of the shields are spaced from the jaws. A pair of sheaves 8 is mounted between each jaw and its respective shield 7. The jaws 5 are apertured, as at 9, intermediate their ends, adjacent the upper ends of the shields 7. The numeral 10 designates a U-shaped member, in the form of a clevis or the like, which has journaled between its ends, a pair 65 of sheaves 11. A continuous cable 12 is trained over the sheaves 11, through the opening 2, through the apertures 9, and over the sheaves 8, to form a sling portion 13, which will be disposed about the rock, as is 70 indicated to advantage in Figure 2. The weight of the rock, when supported between the sling portions 13 of the endless cables 12 will tend to draw this cable tightly about the rock and draw the jaws toward each other, 75 so that the spurs 6 dig into the rock. A cable 15 has its ends attached to intermediate portions of the jaws 5, as at 16, and when the rock is delivered, so as to rest on a sup- 80 port, the cable 15 may be lifted up, thus releasing the jaws and sling portions 13, from the rock. The sling portions 13 and the jaws may be very easily engaged with the rock, as is apparent.

It is thought that the construction, opera- 85 tion, and advantages of this sling will now be clearly understood, without a more detailed description thereof.

The present embodiment of the invention has been disclosed, merely by way of ex- 90 ample, in order to show an embodiment, which will attain all of the features of ad- vantage enumerated as desirable in the state- ment of the invention and the above descrip- tion. It will be apparent that numerous 95 changes in the details of construction, and in the combination and arrangement of parts may be resorted to, without departing from the spirit or scope of the invention as hereinafter claimed or sacrificing any of its ad- 100 vantages.

A light cable hanging from the main der- rick is provided with a hook on the suspend- ed end for the purpose of hooking on to the bail and hoisting on same after disengaging 105 from the rock with the idea of holding the jaws spread and retaining the slack as it comes off the rock.

Having thus described my invention, what I claim as new is:

1. In a sling structure of the class described, a plate having an opening, a pair 5 of jaws having openings pivotally mounted on the ends of the plate, sheaves journaled on the extremities of the jaws, a clevis, sheaves supported in the clevis, and an endless cable trained over the sheaves in the clevis, 10 through the openings in the jaws, and over the sheaves on the jaws for forming sling portions.

2. In a sling structure of the class described, a plate, links pivoted to the ends of 15 the plate, said plate provided with an intermediately disposed opening, jaws pivoted to the links, shields provided on the outside of the jaws and having their intermediate portions spaced from the jaws, sheaves 20 journaled between the jaws and the shields, said jaws provided with apertures, spurs on the inner sides of the extremities of the jaws, a U-shaped clevis, a pair of sheaves journaled in the U-shaped clevis, and an endless cable 25 trained over the sheaves in the clevis, through the opening in the plate, through the apertures in the jaws, and over the sheaves between the jaws and the shields, and a second cable attached at its ends to the intermediate portions of the jaws.

the clevis, through the opening in the plate, through the apertures in the jaws, and over the sheaves between the jaws and the shields.

3. In a sling structure of the class described a plate, links pivoted to the ends of 30 the plate, said plate provided with an intermediately disposed opening, jaws pivoted to the links, shields provided on the outside of the jaws and having their intermediate portions spaced from the jaws, sheaves journaled 35 between the jaws and the shields, said jaws provided with apertures, spurs on the inner sides of the extremities of the jaws, a U-shaped clevis, a pair of sheaves journaled in the U-shaped clevis, and an endless cable 40 trained over the sheaves in the clevis, through the opening in the plate, through the apertures in the jaws, and over the sheaves between the jaws and the shields, and a second cable attached at its ends to 45 the intermediate portions of the jaws.

In testimony whereof I affix my signature.

ELDEN L. SMITH.
